UNITED STATES PATENT OFFICE.

BERNIS M. SHIPLEY, OF DAYTON, OHIO, ASSIGNOR, BY MESNE ASSIGNMENTS, TO THE NATIONAL CASH REGISTER COMPANY, OF DAYTON, OHIO, A CORPORATION OF MARYLAND.

CASH REGISTER.

Application filed April 27, 1923. Serial No. 635,027.

This invention relates to cash registers, and more particularly to release mechanism therefor. It is adapted to be applied to a machine of the general type shown and described in the patents to Fuller, Nos. 1,242,170 and 1,394,256, issued Oct. 9, 1917, and Oct. 18, 1921, respectively, and an application of B. M. Shipley, No. 451,508, filed March 11, 1921.

10 The principal object of this invention is to provide an extremely flexible form of release and interlocking mechanism for machines of this class which is capable of being constructed in a plurality of forms adapted to the particular system with which the machine is to be used.

Another object of the invention is to provide mechanism so constructed that a key in each of a plurality of banks may operate means to permit release of the machine.

Still another object is to have the releasing mechanism arranged so that it is necessary to depress a key in each of several banks before the machine can be released.

With these and incidental objects in view, the invention consists of certain novel features of construction and combinations of parts, the essential elements of which are set forth in appended claims and a preferred form of embodiment of which is hereinafter described with reference to the drawings which accompany and form part of this specification.

35 Of said drawings:—

Fig. 1 is a detail rear view of the release mechanism.

Fig. 2 is a detail side view of the release mechanism, together with part of the first control bank and the motor bar.

Fig. 3 is a detail side elevation of the interlocking mechanism between the release shaft and one of the control banks, taken on the line 3—3 of Figs. 1 and 7.

45 Fig. 4 is a detail side elevation taken on line 4—4 of Figs. 1 and 7.

Fig. 5 is a detail side view of part of the release mechanism.

50 Fig. 6 is a detail view of the spring and arm which rock the release shaft when it is released.

Fig. 7 is a rear view of a release mechanism, requiring depression of a different combination of keys from that shown in Fig. 1.

Fig. 8 is a detail sectional view of the release mechanism taken on line 8—8 of Figs. 1 and 7.

Fig. 9 is a rear view of a release mechanism requiring depression of a different combination of keys from that shown in either Fig. 1 or Fig. 2.

Fig. 10 is a detail view showing the means whereby the hook members shown in Fig. 9 are connected to the yokes.

In general.

In machines of the type to which this invention is adapted to be applied there are usually a plurality of banks of amount 70 keys and a plurality of banks of control keys. The control keys are for the purpose of controlling the selection and engagement of the various totalizers corresponding thereto on adding and totalizing operations. 75 These machines are normally locked against operation and the usual means for releasing the machines for operation is a motor bar which, upon its depression, releases the machine for operation and also closes the 80 motor circuit if the machine is operated by an electric motor.

The release mechanism which exemplifies this invention may be used in any one of a large number of different forms of 85 which this mechanism is capable, depending upon the system with which the machine is to be used. For instance, a common form of the release mechanism is that in which it is controlled by three banks of control keys and a motor bar. Depression of a key in each of the three banks is necessary before the machine can be released by the motor bar.

Another form which is shown herein is that in which keys in the first and second banks of control keys must be depressed before the machine can be released and a key may or may not be depressed in the third bank, as desired.

Still a different form is one in which the depression of a key in any of the three

banks of control keys will unlock and release the machine in conjunction with the motor bar. These forms above noted, and which will be hereinafter described, are taken simply as representative examples of some of the various uses to which the novel mechanism may be put. However, the invention is capable of being adapted for use in a great many other combinations, which it is thought unnecessary to show and describe herein, without in any way departing from the spirit thereof, and it is not desired to limit the invention in any way to the three forms of mechanism shown herein.

15 Release shaft.

In all machines of this type there is a release shaft 25 which is adapted to be rocked in a clockwise direction (Fig. 6) by means of a powerful spring 26, which is compressed between a pair of members 27 carried by a stud 28 projecting through a slot 29 in a link 30, and a shoulder formed in said slot. The stud 28 is carried by an arm 31 fast on the release shaft. In the normal position of the parts the release shaft is prevented from being rocked under the influence of the spring 26 by the engagement of a half-round stud 32 (Fig. 8) carried by an arm 33 pinned to the shaft 25, with a pair of pawls 34 and 35 (Figs. 1, 7 and 9) loosely mounted on a shaft 36 supported by the machine side frames 37. It can be seen from Fig. 8 that so long as the pawls 34 and 35 remain in alignment with the flat face of the half-round stud 32 the shaft 25 cannot be rocked clockwise by the spring 26 to release the machine. When the machine is released, as will be hereinafter described, the releasing movement of the shaft 25 is limited by the engagement of a projection 38 (Fig. 6) of the arm 31 with a pin 39 carried by the right hand side frame 37.

Release by motor bar.

45 When the proper keys in the keyboard have been depressed the machine is adapted to be released by a motor bar 45 (Fig. 2), the shank of which has a bifurcated end 46 adapted to surround a pair of studs 47 carried by a plate 48 which in turn is slidably mounted on a pair of studs 49 and 50, supported in the right hand side frame 37, omitted from Fig. 2, but shown in Fig. 1. The plate 48 also carries a pin 51 which cooperates with the bifurcated end of one arm of a lever 52 which is pivoted on a stud in the right hand side frame 37 (Fig. 1). At its opposite end the lever 52 carries a pin 53 which projects through the bifurcated end of an arm 54 loose on the shaft 36. The arm 54 is made integral with a hook member 55 by means of a yoke 56. When the motor bar 45 is pressed in, the hook member 55 will be rocked clockwise about the shaft 36 (Fig. 2).

A pin 57 (Figs. 1 and 2) carried by an arm 58 is adapted to cooperate with the inner periphery of the hook member 55 and the arm 58 will thereby be rocked clockwise upon the clockwise movement of the hook member 55. Integral with the arm 58 is a bifurcated arm 59 connected thereto by a yoke 60 (Figs. 2 and 8). The bifurcated portion of the arm 59 surrounds a pin 61 carried by the pawl 34, which is the right hand one of the two pawls 34 and 35 which normally obstruct the movement of the flattened stud 32 and thereby prevent the release of the machine. The pawl 35 is under the control of the keys in the control banks and will have been rocked out of engagement with the stud 32 upon the depression of said keys in a manner which will be hereinafter described. Therefore when the arm 58, yoke 60 and arm 59 are rocked clockwise it can be seen from Fig. 8 that the pawl 34 will be rocked counter clockwise about the shaft 36 and will thereby become disengaged from the stud 32. As soon as both of the pawls 34 and 35 are raised out of the path of the stud 32, this stud, together with the arm 33, shaft 25 and arm 31 will be rocked clockwise under the influence of the spring 26 far enough to permit operation of the cash register. The stud 32 will then be positioned between the pawls 34 and 35 and another pawl 62 loose on the shaft 36 and connected to the pawl 34 by a spring 63.

Release by first control bank—Control by 100 second and third banks.

The first of the three examples of the uses to which the present invention may be put will now be described. It contemplates mechanism enforcing depression of keys in all three control banks prior to a release of the machine by the motor bar 45.

In order to prevent the release of the machine until a key has been depressed in the first, second and third control banks there are provided two members 68 and 69 fast on the shaft 25 (Figs. 1, 4 and 5). These members 68 and 69 have projecting portions 70 which normally lie beneath hooks 71 and 72 loose on the shaft 36. There are two of the hooks 71 which cooperate with the member 68, one of the hooks being operated by the second control bank and the other by the third bank. The hook 72 which cooperates with the member 69 is operated by the first control bank. Each of the hooks 71 and 72 is connected by a yoke member 73 to an arm 74 also loose on the shaft 36.

As is well known in the art, each of the control banks in machines of this class is provided with a detent 75 (Fig. 4) which at its upper end is pivotally carried by an arm 76 pivoted to the frame 77 (Fig. 2). Upon the depression of any of the keys in the three control banks the detent appropriate to the

particular bank operated will be moved downwardly. The arm 76 has a projecting portion 78 which carries a pin 79 adapted to cooperate with the arm 74 for this particular bank. It can be seen from Fig. 4 that when the detent 75 is moved down upon the depression of a key in its bank the arm 76 will be moved clockwise and the pin 79 will contact with and rock the arm 74, and through arm 74 rock the yoke member 73 and hooks 71 or 72, depending on which bank of control keys has been operated, counter-clockwise about the shaft 36 far enough to remove the hook portions from above the projections 70 of the members 69, which will permit the machine to be released. As there is one of these hooks 71 or 72 appropriate to each bank of control keys in the example now being described, it can be seen that it will be necessary to depress a key in each of the three control banks in order to permit the machine to be released.

The yoke member 73 for the first bank of control keys has a downwardly extending portion 80 which carries a pin 81 projecting through a bifurcated portion 82 of a yoke member 83 loose on the shaft 36. Integral with the left hand end (Fig. 1) of the yoke member 83 is the pawl 35 previously described, which cooperates with the half-round stud 32 to normally prevent the release of the machine. It has been previously described how the yoke 73 for the first bank is rocked counter-clockwise (Fig. 5) upon the depression of any of the keys of said bank; and, due to the connection of the pin 81 with the bifurcated portion 82 of the yoke 83 this yoke and its corresponding pawl 35 will be rocked counter-clockwise far enough to disengage the pawl from the half-round stud 32 and thereby release the machine in so far as the control keys are concerned.

For the purpose of compelling depression of control keys before depression of the motor bar can release the machine, the pawl 35 is made slightly longer than the pawl 34, so that the motor bar will not remain depressed unless a control key has been previously depressed. The point of the pawl 35 which is operated from the control keys, is chamfered, so that the pawl may move back into the path of the stud pin 32, when a depressed control key is released manually, as for example, when the wrong control key has been depressed. This makes it necessary to have a control key in depressed position at the time the machine is released whether the key is depressed prior or subsequently to or simultaneously with the release key.

Release by first bank—Control by second bank—Depression of key in third bank optional.

65 The second of the three forms to be de-

scribed herein, in which the invention may be used, will now be described. In this form it is desired to have the depression of the keys in the third control bank optional with the operator. A depression of a key in the second control bank is required to permit the release of the machine and the depression of a key in the first control bank is necessary not only to permit the release of the machine but to partially operate the release mechanism, as was described in connection with the first example. The mechanism which is adapted to produce the results above mentioned is shown in Fig. 7, and it can be seen by looking at this figure that the mechanism is substantially the same as that shown in Fig. 1. In order to make the third control bank free, the hook 71, yoke 73 and arm 74 for this bank are left out and the member 68 cooperates only with the arm 71 for the second transaction bank. With this exception the two mechanisms are identical, as above described. When a key in the second transaction bank is depressed its detent 75 will engage the arm 74 and through the yoke member 73 will rock the hook 71 out of the path of the projection of member 68, thereby permitting the release of the machine in so far as this bank is concerned. The depression of a key in the first transaction bank therefore will, through the detent 75, rock the arm 74, yoke 73 and hook 72 to remove this hook from the path of the projection 70 of the member 69. The rocking movement of the yoke 73 will be transmitted to the yoke 83 by means of the pin 81 and the bifurcated portion 82 and will thereby rock the pawl 35 out of engagement with the stud 32, which will release the machine in so far as the first transaction bank is concerned. If the motor bar 45 is then depressed the pawl 34 which also cooperates with the stud 32 will be rocked out of engagement therewith as above described and the spring 26 will rock the shaft 25 to its released position.

Release of machine by depression of a key in either the first, second, or third control bank.

When it is desired to release the machine by depression of a key in the first, second or third control banks the mechanism used is like that shown in Fig. 9. Only the mechanism on shaft 36 has been shown in this figure, as the mechanism on the shaft 25 is, with one exception, identical with that shown in Fig. 7, and just above described. The main difference between the mechanism shown in Fig. 9 and the mechanism shown in Figs. 1 and 7 is the fact that there is only one of the hook members 71 shown in Fig. 9. This is the hook which is adapted to cooperate with the member 68 shown in Fig. 7. A long yoke member 85

is provided in this construction, which connects the arm 74 for the first bank with the arm 74 for the third bank. The arm 74 for the second bank, as well as the hook 71, are formed with bifurcated portions at their lower ends which cooperate with the yoke 85 and cause these members to move with the members 74, before mentioned. The yoke 85 is connected to the yoke 83 by means of the pin 81 and the bifurcated portion 82 shown in Fig. 5, and above described. It can therefore be seen that the depression of a key in any of the three control banks will, through the detent appropriate thereto, rock its corresponding arm 74 counter-clockwise and through the yoke 85 rock the hook 71 out of engagement with the portion 70 of the member 68, as above described. As the yoke 85 is connected to the yoke 83, it is evident that if the yoke 85 is rocked counter-clockwise the yoke 83 will also be rocked in a like direction and the pawl 35 which is integral with the yoke 83 will be rocked out of engagement with the stud 32 and thereby permit the machine to be released in so far as the control keys in all three banks are concerned. The depression of the motor bar will then rock the pawl 34 out of contact with the stud 32 and permit the rotation of the shaft 25 under the influence of the spring 26, as above described.

Mechanism for disengaging hooks on totalizing operations.

When the machine herein disclosed is operated to take either a total or sub-total from any of its totalizers, it is essential that all of the hooks 71 and 72 be rocked out of the path of the members 68 and 69 so that the machine can be released when only one of the control keys has been depressed. This function is accomplished in the following manner. Every machine of this type is provided with a pivoted plate 91 (Figs. 1, 2 and 7) which is commonly known as the "total lever plate". When it is desired to take either totals or sub-totals from any of the totalizers it is necessary first to rock this plate either counter-clockwise or clockwise, as seen in Fig. 2, and as is well known in the art to one of a plurality of positions. The plate 91 has a slot 92 formed therein into which projects a roller 93 carried by an arm 94 fast on a shaft 95 which is rotatably mounted in the differential supporting frames of the machine. Also fast on this shaft are two arms 96 and 97 (Figs. 1 and 4) which carry pins 98, the normal position of which is just below the ends of the two arms 99 which are loose on the shaft 36. There is one of these arms 99 for the first bank of control keys (Fig. 1) and another of said arms which is adapted to cooperate with

both the second and third banks of control keys. The arms 99 carry pins 100 (Figs. 4, 7 and 9) which lie directly back of the hooks 71 and 72, above described.

From the above description it is evident that when the total lever is moved to any of its totalizing or sub-totalizing positions the plate 91 will be rocked either counter-clockwise or clockwise, and due to the conformation of the slot 92 the pin 93 which cooperates therewith will be rocked upwardly. As this pin 93 is carried by the arm 94 this arm and the shaft 95 will be rocked clockwise (Fig. 2). The arms 97 being fast on the shaft 95 will also be rocked clockwise (Fig. 4), which movement will bring the pins 98 into contact with the lower ends of the arms 99 and will thereby rock these arms counter-clockwise about the shaft 36 (Fig. 4). As the arms 99 carry the pins 100 these pins will engage with the hooks 71 and 72 and will rock these hooks counter-clockwise far enough to remove them from the path of movement of the portions 70 of the members 68 and 69 and through the yoke member 83 and the movement of shaft 95, just described, the pawl 35 will be raised out of engagement with stud 32 and thereby permit the release of the machine in the manner above described.

It is obvious that the motor bar and its pawl 34 may be omitted and the first bank employed as a release bank. In this case one of the keys in the first bank would be employed to release the machine for entering amounts on, or taking amounts from, totalizers corresponding to keys in the other control banks. This construction of the release bank is shown in the application referred to.

Interlocks.

An interlock is provided to prevent release of the machine if any of the control keys are only partially depressed or to prevent depression of any of the control keys after the machine has been released. This mechanism will now be described.

Cooperating with each bank of control keys is a detent 101 which has beveled portions 102 which cooperate with pins 103 carried by each of the control keys (Figs. 2 and 3). It is evident from Fig. 3 that when a control key is depressed its pin 103 will move the detent 101 downwardly until the pin 103 passes the beveled portion 102 of said detent, whereupon the detent will be returned to its normal position, as shown

depressed keys in their depressed positions. The detent 101 is supported by an arm 110 which carries a pin 104 projecting through a bifurcated portion 105 of an arm 106 loose on the shaft 36. The arm

106 carries a portion 107 which, when a key is partially depressed and the detent 101 is moved downwardly thereby, will be raised into the path of an 5 arm 108 fast on the shaft 25, which is the release shaft. It can therefore be seen that when one of the control keys is depressed only part way the arm 106 will be rocked counter-clockwise by the pin 104 to a position in which the portion 107 will obstruct the movement of the arm 108, which 10 will therefore prevent the release of the machine while the parts remain in this position. If the key is fully depressed, however, the detent 101 returns to its normal 15 position, as shown in Fig. 3, and the portion 107 of arm 106 is rocked clockwise out of the path of the arm 108 and therefore there will be no obstruction to the movement 20 of this arm and the releasing movement of shaft 25 can take place. There is one of the arms 106, together with its corresponding arm 108, cooperating with each bank of control keys. See Fig. 1.

25 It is also apparent from Fig. 3 that when the machine is released and the shaft 25 rocked clockwise, the arm 108 will also be rocked into the path of the portion 107 of arm 106 and therefore it will be impossible 30 to depress any of the control keys as the detent 101 will be locked against movement until such time as the shaft 25 is restored to its normal position.

The detent 101 is moved downwardly to 35 release the keys by engagement of an arm 109 with the horizontal portion of arm 110 upon restoring movement of shaft 25 to which it is secured. The arms 109 and 108 may be integrally formed, as shown.

40 While the form of mechanism herein shown and described is admirably adapted to fulfill the objects primarily stated, it is to be understood that it is not intended to confine the invention to the forms of embodiment herein disclosed, for it is susceptible of embodiment in various forms, all coming within the scope of the claims which 45 follow.

What is claimed is:-

50 1. In a machine of the class described, the combination of a release shaft, means adapted normally to rock said shaft, a member carried by said shaft, a plurality of means for obstructing the movement of said member, a single means for removing one of said plurality of obstructing means, and a plurality of groups of manipulative devices for removing the other of said obstructing means.

60 2. In a machine of the class described, the combination of a main operative mechanism, a pair of pawls for locking said main operating mechanism, a plurality of banks of keys for rocking one of said pawls to

release said main operating mechanism, and a single manipulative means for rocking the other of said pawls.

3. In a machine of the class described, the combination of operating means, a pair of pawls for locking said operating means, 70 a plurality of banks of keys, means operated by any one of said banks of keys for rocking one of said pawls to release said operating means, and a single key depression of which will rock the other of said 75 pawls.

4. In a machine of the class described, the combination of operating means, a pawl for locking said operating means, a plurality of groups of keys, hook members for preventing the release of said operating means, means operated by the depression of a key in certain of said groups for disengaging said hook members, and means operated by the depression of a key in certain other groups for rocking said pawl to permit the release of said operating means.

5. In a machine of the class described, the combination of operating means, a pawl for locking said operating means, hook members for preventing the release of said operating means, a plurality of groups of depressible keys, a detent operated by the depression of a key in any of said groups, an arm operated by said detent for disabling said hook members, and a second detent operated by certain ones of said groups the movement of which will rock said pawl to release said operating means.

6. In a machine of the class described, the combination of a release shaft, a spring adapted normally to rock said shaft, an arm carried by said shaft, a stud mounted on said arm, a plurality of pawls adapted to engage said stud to prevent the rocking of said shaft, a plurality of banks of keys, means whereby depression of a key in each bank is necessary to rock one of said pawls out of engagement with said stud, and a single key for rocking the other of said 110 pawls out of engagement with said stud to release the machine.

7. In a machine of the class described, the combination of a release shaft, a plurality of projections fast on said shaft, a plurality 115 of hooks engaging said projections to prevent the movement of said release shaft, a plurality of means for disengaging said hooks on certain operations, and a single means for disengaging all of said hooks on 120 certain other operations.

8. In a machine of the class described, the combination of a release shaft, a plurality of projections fast on said shaft, a plurality of hooks engaging said projections to prevent the movement of said release shaft, a plurality of manipulative devices for disengaging said hooks on certain operations,

and a single manipulative device for disengaging said hooks on certain other operations.

9. In a machine of the class described, the combination of a release shaft, a plurality of projections fast on said shaft, a plurality of hooks engaging said projections in order to prevent the movement of said release

shaft, a plurality of banks of depressible keys for disengaging said hooks on adding operations, and a shiftable lever for disengaging said hooks on totalizing operations.

In testimony whereof I affix my signature.

BERNIS M. SHIPLEY.
